UNITED STATES PATENT OFFICE.

WILLIAM J. HAYNES, OF ST. LOUIS, MISSOURI, ASSIGNOR TO HAYNES-LANGENBERG MANUFACTURING COMPANY, OF ST. LOUIS, MISSOURI, A CORPORATION OF MISSOURI.

HEATING APPARATUS.

1,284,893.

Specification of Letters Patent. Patented Nov. 12, 1918.

Application filed July 1, 1915. Serial No. 37,620.

To all whom it may concern:

Be it known that I, WILLIAM J. HAYNES, a citizen of the United States, residing at the city of St. Louis and State of Missouri, 5 have invented a new and useful Heating Apparatus, of which the following is a specification.

This invention relates to improvements in heating apparatus and consists in the novel 10 construction hereinafter shown.

An object of the invention is to provide a heating apparatus including in combination means for heating a supply of air and means for heating a supply of water including provision for promoting the fuel combustion. 15

Another object of the invention is to provide a heating apparatus including primary and secondary fuel supporting grates with provision for effecting a down-draft passage 20 of the products of combustion from the primary grate structure over the secondary grate structure whereby substantially complete combustion is effected, in combination with means for converting the apparatus at 25 the will of the operator so as to cause a direct or up-draft passage of the products of combustion.

Another object of the invention is to embody in an apparatus of the class described 30 a novel means of supplying and discharging the water supply to and from the heating unit therefor.

Having in view the objects specifically mentioned and also additional advantages 35 attainable by the construction of the present invention which will be apparent to those skilled in the art without specific mention, I have combined, designed and arranged a heating apparatus as hereinafter disclosed 40 reference being made to the accompanying drawings in which—

Figure 1 is a front elevation of an apparatus embodying the invention with the outer shell or casing broken away.

Fig. 2 is a rear elevation of the same structure.

Fig. 3 is a cross section through the apparatus taken substantially on the line 3—3 of Fig. 1.

Fig. 4 is also a cross section through the apparatus taken substantially on the line 4—4 of Fig. 1.

Fig. 5 is a view similar to Fig. 1 with portions of the heating drum and associated 55 parts being shown in section.

Fig. 6 is a bottom plan view of the primary grate structure, and

Fig. 7 is a cross section through the primary grate structure.

In the embodiment of the invention illustrated in the drawing the outer shell or casing 1 of the apparatus is mounted upon a base 2. A cylindrical metal shell or drum 3 is supported by the base 2 and is incased within the casing 1. A dome 4 is provided at the top of the drum 3. A lining or wall 6 of fire brick or other refractory material is provided. The lining 6 does not extend throughout the full length of the drum as it is only necessary to line such portion thereof 70 as constitutes the fire pot or combustion chamber.

A primary grate structure 7 comprising a hollow casting of the construction shown particularly in Figs. 6 and 7 is supported 75 transversely of the fire pot substantially intermediate of the same being set into recesses in the lining 6 in the manner clearly shown in Fig. 4 of the drawing. The primary grate structure 7 is preferably constructed as shown and includes a series of parallel hollow grate bars 8 integrally united at their ends with segmental end members 9, there being a free interior communication 80 between the members 8 and 9 as is clearly 85 shown by the cross sectional view thereof illustrated in Fig. 7. It will be observed that the grate bars 8 are formed with downwardly inclined side walls, thus the passageways between them are smaller at the top 90 than at the bottom. This construction permits the ready passage of masses of the fuel through the grate structure and prevents the grate from becoming clogged. As the grate is stationary the agitation of the fuel is 95 effected by a poker when it is desired to force the passage of fuel from the primary grate structure to the secondary grate structure therebelow. However, even during the process of normal combustion and without 100 any artificial agitation there will be passage of portions of the bed of fuel supported by the primary grate structure through the grate, the same dropping down upon the secondary grate structure where its combustion is completed.

The primary grate structure divides the fire pot into an upper combustion chamber A and a lower combustion chamber B, access being had to the chamber A through a fire 110

box liner casting 10 provided with a damper door 11.

5 A secondary grate structure comprises a series of rockable bars 12 of known arrangement and construction. The secondary grate structure constitutes the bottom of the chamber B. A fire box liner 13, equipped with a fire door 14, provides access to the chamber B; and an ash pit opening, provided with an ash pit door 15, provides access to the ash pit for the purpose of removing the accumulated products therefrom, said ash pit door being equipped with a damper 16 for the admission of air when required.

10 15 A radiator 17 is supported adjacent to the upper portion of the drum or case 3 and extends substantially around one half the circumference thereof. A conduit 18 connected into the drum 3 and the radiator 17 provides a passage between the upper part of the drum and the radiator. The passage 18 is controlled by a damper 19 mounted upon a rod or shaft 20 which extends outwardly through the casing 1 at one end and is provided with a handle 21 whereby the damper 19 may be manipulated for opening or closing the passage between the upper portion of the drum and the radiator. A discharge flue 22 leads from the radiator. The radiator is also provided with removable clean-out caps 23 whereby access to the interior thereof may be obtained for the purpose of removing therefrom the usual accumulated deposits.

25 30 35 A series of conduits 24 leading from the walls of the chamber B extend into the lower portion of the radiator 17.

In the down-draft operation of the apparatus the products of combustion from the burning bed of carbonaceous material supported by the primary grate structure pass downwardly into the chamber B through a heated zone created by the combustion of the fuel supported by the secondary grate structure. The primary combustion, supported by air admitted through damper 11, with damper 19 closed, that is effected in the chamber A is insufficient to fully reduce the volatile combustible products, the same, therefore, carried down into the chamber B being converted as they pass therethrough into fixed gases substantially free from combustible material. Moreover, the secondary grate structure is continually fed by the downward passage of the solid combustible material from the primary grate structure where the combustion of the same is completed. Thus substantially all of the heat units from the fuel are utilized, effecting a large saving of fuel in producing a given amount of heat energy. Moreover, as substantially complete combustion is effected in the chamber B of the volatile products passing thereto from the upper chamber A, the gases passing from the chamber B

70 through the conduits 24 into the radiator 17 and thence through the discharge flue 22 are fixed gases free from hydrocarbon. Thus the apparatus gives off substantially no smoke or free gas.

75 Whenever it is desired to operate the apparatus on the direct draft principle the damper 19 is opened and the products of combustion will pass therethrough directly into the radiator from the upper part of the drum 3. This may be desired on different occasions, and is of considerable advantage when it is desired to open either of the lower doors, as, for instance, when the door to the ash pit is open to enable the ashes to be removed. By opening the damper 19 an up-draft is established, thus preventing the fumes, gases and smoke from entering the room while the lower door is open.

80 85 The connections for supplying and discharging the water to and from the interior of the primary grate structure includes a supply pipe 25 connected directly into the primary grate structure and leading from any suitable source of continuous supply at the opposite side and also directly connected into the grate structure, is a service pipe 26 leading to any suitable source, for instance, a circulatory hot water radiator system. A return passage 27 is connected into the same end of the grate structure with the pipe 26. An outlet pipe 28 is connected into the grate structure adjacent to the supply pipe 25. The pipe 28 may be connected into any distributing system, for instance, into a system 90 for hot water supply to a building.

95 In the embodiment shown I have included a faucet controlled passage 29 for withdrawing the water from the system for the purpose of draining or cleaning out the same or for supplying hot water at this point. It will be observed that by utilizing the connections just described a continuous circulation through the grate structure will be maintained, which, in addition to supplying the hot water heating system, will also effect a cooling of the grate preventing the same from being burned. A thermometer 30 may be connected into the water system for ascertaining the temperature of the water.

100 105 110 115 It will of course be understood that the distribution of the heat may be effected in the usual manner by a plurality of service conduits connected into the outer casing in the usual manner.

120 I am aware that numerous changes in details of construction may be made without departing in the least from the spirit and scope of my invention. I do not limit myself, therefore, to the exact structure shown and described but what I claim and desire to secure by Letters Patent is:

125 A heating apparatus comprising a drum, a secondary grate arranged in and near the lower end of the drum, a primary grate 130

arranged above the secondary grate, a combustion chamber between the grates, a combustion chamber above the primary grate, a radiator about the drum and spaced therefrom, a damper controlled conduit leading from the combustion chamber above the primary grate to the radiator, and a series of radiating flues arranged about the drum and leading at their upper ends into the 10 radiator, the lower ends of the flues opening

into the combustion chamber between the grates, said flue openings into the combustion chamber being in annular spaced relation.

In witness whereof I have signed this specification in the presence of two subscribing witnesses. 15

WILLIAM J. HAYNES.
